INTERLOCKING WALL JOINT
CONSTRUCTION

Milton B. Terrell, Columbus, Ohio

Application September 13, 1937, Serial No. 163,583

4 Claims. (Cl. 20—92)

The invention to be hereinafter described relates to an interlocking wall joint construction.

Lap-joints of many kinds and types, with one part overlapping or underlapping another are well known. Dove-tailed joints of many kinds are widely known. Simple interfitting, complementary or match joints are universally used. They frequently appear in imitation brick or stone or similar surfaces. As heretofore constructed, these joints have not been self sustaining against pressures on one face or the other of a wall but, instead, required strong backing or support, as well as securing means, or they have been subject to leaks, or they have been complicated and difficult to assemble or to maintain in shape, or they have been of special construction. They have more generally been used as veneers and similar surfacing work, requiring a foundation, backing or support.

The main objects of the present invention are to overcome the above and other drawbacks and provide a wall joint of simple, efficient, economical construction which may be easily made as parts of a unit or units of standard dimensions, as well as of units of other dimensions for a wall, partition or the like which may be easily and quickly erected and as readily dismantled and yet, when erected, will be weather proof, securely interlocked and thoroughly self sustaining at all joints. It provides a complete wall body including the surface. It may, of course, be made as a surface or veneer and attached to a wall body.

The units or elements carrying the joint members may be of any thickness desired and, of course, of any material desired. They may be of stone, wood, concrete, metal, plastic composition, etc., and they may be pressed, stamped, cut, molded, or otherwise made.

One preferred method of manufacture is by pressing or molding under considerable pressure from plastic material such as is used in the making of what is generally known as composition roofing. By such a method, the units may be produced in large quantities and of any desired thickness, within considerable limits.

In order to more clearly disclose the construction, operation and use of the invention, reference should be had to the accompanying drawings forming part of the present application. Throughout the several figures of the drawings like reference characters designate the same parts in the several views.

In the drawings:

Fig. 1 is a side elevation of the invention, looking toward a wall from the outside;

Fig. 2 is a like view, with joint partly separated;

Fig. 3 is a vertical lateral cross section, looking in the direction of the arrows 3—3;

Fig. 4 is a like view on the same line, but looking in the opposite direction, as indicated by the arrows 4—4;

Fig. 5 is a view similar to Fig. 1, but of the opposite side or face of the invention; and,

Fig. 6 is a view showing a section of wall built with the invention.

In the drawings the entire wall body is shown built from the units of this invention. It will be understood that the invention is equally applicable for wall surfacing, such as veneering or the like and applied to either surface of a wall.

The joint selected for illustration of the invention is made from plastic material similar to that used in making composition roofing and is molded under pressure to the form and size desired. The joint is formed partly on one unit and partly on another. In other words, male and female or complementary joint elements are formed on adjacent edges or ends of adjoining units. Accordingly, production and assembly are greatly simplified by making each unit 1 with joint members at opposite ends, those at one end being male and those at the opposite end being female, or those at one end being complementary to those at the other end. Therefore, every unit so made will have a joint element at each end exactly complementary to a cooperating joint element on the opposite end of every other such unit. The units may be perfectly plain or may be given any desired decorative surface such as imitation brick or stone, etc. for simplicity, that selected in the drawings and description is perfectly plain.

Constituting the joint are four or more tongues 2, two or more extending from the end of each of two cooperating units. As far as the joint, itself, is concerned, to make the units fully cooperative with all other units of the invention, or interchangeable, four tongues are necessary, two on each end, providing fully complementary joint parts on opposite ends of all units. When assembled, one tongue of each joint lies between the two tongues of the respective other unit joint part and occupies the intervening recess or tongue socket, as most clearly shown in Fig. 2. With interchangeable units each having two tongues at each end with an intervening tongue recess or socket, the inner tongue or that re-

removed from the unit edge, in assembly, is received between the two tongues of the other unit and occupies the intervening recess. At the same time, the other tongue, at the edge of the 5 unit is received by and occupies the shoulder or notch extending from the inner tongue of its unit to the outer edge. More than four tongues and cooperating parts may be used for each joint but are not necessary. Each tongue 10 of the male joint element of a unit is provided with an underlapping lip 3 extending the full length of the respective tongue and across the greater part of the width of the free end of the tongue. The width of this lip should be sufficient 15 to provide adequate joint bearing area and complete weatherproof seal against leakage and wind, but may be varied within the limits of those requirements. The short branch terminates inwardly of its tongue edge a distance equal 20 to the width of a lip, leaving a longitudinal overlap lip 4 of each male element tongue, extending the full length of the tongue. This lip 4 is in a plane offset from but parallel to the lip 3, the offset being just equal to the lip thickness. 25 Consequently, lip 4 may be considered as a shoulder, or the tongue may be considered as channeled longitudinally to receive the cooperating longitudinally extending underlapping lip 5 of the female joint element which lip is of the same 30 dimensions as the channel. Cooperating with each longitudinal portion of the underlap lip 3 is a corresponding or complementary overlapping lip 6 of a tongue of the female member. Similarly cooperating with short branch 7 of each underlap lip 3 is a complementary overlap lip 8 35 of corresponding dimensions. There are two such underlap lips 7 at the outer or free ends of the tongues of the male members and two at the inner ends of the tongues, one extending between tongues and the other from the upper 40 tongue to the edge of the unit. For convenience they may be referred to as outer lips 7 and inner lips 9. Cooperating with underlap lips 9 are corresponding and complementary overlap lips 10 45 of the same dimensions and carried by the outer free ends of the female tongues.

The full length of the top edge of each unit is provided with an underlap lip 11 and the full length of the bottom edge with a corresponding 50 overlap lip 12 so that, when assembled in place, the bottom edge of one unit overlaps the top edge of the unit immediately below. The lip 11 may be provided with nail holes 13, at intervals for nailing the units to suitable frame members. 55 The lip 12 completely covers any such securing devices and, at the same time, makes a weather tight joint.

As stated above in connection with lip 4, the overlapping parts may be considered as shoulders, or it may be considered that the respective unit ends are provided with recesses, or channels of corresponding dimensions.

It will be noticed that the male joint element comprises two parallel spaced, approximately Z-shaped continuous underlap lips each having sections or portions 3, 7 and 9. Between the inner end of one Z and the outer end of the other extends the longitudinal overlap lip 4 of the male tongue. It will also be noticed that the female 60 joint element comprises two parallel, spaced approximately Z-shaped continuous overlap lips, shoulders, recesses or channels, each having the portions 6, 8 or 10. They are also parallel to the underlap Z-lips. Between the inner end of one 70 Z and the outer end of the other extends the

longitudinal underlap lip 6 parallel with overlap lip 4. The several lips, preferably, are of about one-half the thickness of the units, as shown in Figs. 3 and 4. The underlap Z-lips of the male element are on one face of the block while the 5 cooperating, complementary, overlap Z-lips are on the opposite face. Notice, however, that the intervening overlap lip 4 of the male joint element is on the face opposite to that of its Z-lips and that the intervening underlap lip 5 of the female 10 joint element is on the face opposite to that of its Z-lips.

Refer to Fig. 2. If either the overlap lip 4 or the underlap lip 5 should be omitted there would be no joint interlock between the units. 15 The tongues could be moved perpendicularly to the faces of the units and completely out of alignment. In fact, without those parts in that relation there would be merely an interfit or matching.

By arranging the pair of Z-lips of the male joint element in substantial alignment with those of the female joint element but on parallel planes such that, when assembled, the inner faces lie one on the other, the joint may be easily and 20 quickly slipped together or separated in erecting or tearing down a wall. And when slipped together, the surfaces at the joint will be smooth and flush. The wall face will be perfectly smooth and even, inside and out.

By reversing the positions of the cooperating intervening lips 4 and 5, relatively to that of the pairs of Z-lips, a perfect lock-joint results. Engagement between Z-lips of the male joint element and the Z-lips of the female joint element 25 prevents movement perpendicularly to the face of the units in one direction, while engagement between lips 4 and 5 prevents it in the opposite direction. That same engagement of the various 30 cooperating lips provides a simple, efficient and smooth working guide in sliding the parts together or apart. The whole combination provides a sliding key-lock absolutely preventing separation of the joint in any direction except in the 35 direction of the length of the tongues of the 40 joint.

Refer to Figs. 1 and 2. When this joint is assembled or closed, as in Fig. 1, the lips completely overlap. The joint, shown in full lines in Fig. 1, extends only half way through the unit. At 50 half way, the joint is overlapped by the underlying lips 3, 5, 7 and 9. This completely seals the joint against all wind or rain. In the same way, the top underlap completely blocks off and seals the joint between the bottom edge of the 55 bottom overlap lip 12 and the inner top edge of the units immediately below. The same overlap completely covers all nail holes through lip 11.

The joint is rigid and strongly resistant in all directions perpendicular to either face of the 60 unit. A wall from such assembled units requires only a skeleton frame to nail to. It requires no surfacing, either inside or out. A complete building may be quickly put up by simply erecting the skeleton framework and then assembling these 65 units and nailing in place. And once up it will be found durable and lasting.

It is thought that the construction, operation and use of the invention will be clear from the preceding detailed description.

Many changes may be made in the construction, arrangement and disposition of the various parts of the invention within the scope of the appended claims and it is meant to include all such within this application wherein only one pre- 75

ferred form of the invention has been shown by way of illustration and with no thought of in any degree limiting the claims by any such showing.

Having thus described my invention, what I claim and desire to protect by Letters Patent is:

1. A wall joint unit having formed on each end two spaced tongues, one tongue at each end of each unit being adapted to fit into the corresponding recess between two tongues on the end of another unit, both tongues on each end of each unit being provided with engaging lips along opposite edges, the lips along corresponding tongue edges being directed oppositely to those along the remaining edges relatively to the faces of the unit and the lips of both tongues at one end of one unit, in assembled relation, interengaging the lips of both tongues at one end of a cooperating unit, one pair of interengaging lips being disposed intermediate of two other pairs, each lip of said intermediate pair being directed oppositely to the other and oppositely to both other interengaging lips of the tongues of the same respective unit end whereby, in assembled relation, said units resist forces applied toward either face and maintain interlocked relation until destruction of the joint.

2. A wall joint unit having formed on each end two spaced tongues, one tongue at each end of each unit being adapted to fit into the corresponding recess between two tongues on the end of another unit, both tongues on each end of each unit being provided with continuously extending joint sealing engaging lips along opposite edges, the lips along corresponding tongue edges being directed oppositely to those along the remaining edges, relatively to the faces of the unit, and the lips of both tongues at one end of one unit, in assembled relation, interengaging the lips of both tongues at one end of a cooperating unit, one pair of interengaging lips being disposed intermediate of the two other pairs, each lip of said intermediate pair being directed oppositely to the other and oppositely to both other interengaging lips of the tongues of the same unit end, whereby, in assembled relation, said units resist forces applied toward either face and maintain interlocked relation until destruction of the joint, and maintain a weather proof joint.

3. A wall joint unit having formed on each end two spaced tongues, one tongue at each end of each unit being adapted to fit into the corre-

sponding recess between two tongues on the end of another unit, both tongues at each end of each unit being provided with continuously extending joint sealing engaging lips along opposite edges and across the free ends, said units having similar continuous joint sealing engaging lips across the inner ends of said recesses, the lips along corresponding tongue edges being directed oppositely to those along the remaining edges relatively to the faces of the unit and the lips of both tongues at one end of one unit, in assembled relation, interengaging the lips of both tongues at one end of a cooperating unit, one pair of interengaging lips being disposed intermediate of the two other pairs, each lip of said intermediate pair being directed oppositely to the other and oppositely to both other interengaging lips of the tongues of the same unit end, whereby, in assembled relation, said units resist forces applied toward either face and maintain interlocked relation until destruction of the joint, and maintain a weather proof joint.

4. A wall joint unit having formed on each end two spaced tongues, one tongue at each end of each unit being adapted to fit into the corresponding recess between two tongues on the end of another unit, both tongues on each end of each unit being provided with engaging lips along opposite edges, said lips having approximately one half the thickness of the respective unit end and having their engaging faces in planes parallel with the faces of the unit and approximately midway therebetween, the lips along corresponding tongue edges being directed oppositely to those along the remaining edges relatively to the faces of the unit and the lips of both tongues at one end of one unit, in assembled relation, interengaging the lips of both tongues at one end of a corresponding unit and all tongues lying flush with the respective surface of the assembled joint, one pair of interengaging lips being disposed intermediate of two other pairs, each lip of said intermediate pair being directed oppositely to the other and oppositely to both interengaging lips of the tongues of the same unit end whereby, in assembled relation, said units resist forces applied toward either face and maintain interlocked relation until destruction of the joint, and present a smooth flush surface over the assembled joint.

MILTON B. TERRELL.
